CLAIM

The ornamental design for a hair color bottle mixer, as shown and described.

DESCRIPTION

FIG. 1 is a perspective view of a hair color bottle mixer according to a first embodiment of the present invention, showing the upper bottle combinable with the lower bottle in a protrusion-groove combination manner.

FIG. 2 is a front view of FIG. 1.

FIG. 3 is a rear view of FIG. 1.

FIG. 4 is a left side view of FIG. 1.

FIG. 5 is a right side view of FIG. 1.

FIG. 6 is a top view of FIG. 1.

FIG. 7 is a bottom view of FIG. 1.

FIG. 8 is an expanded top view of FIG. 1.

FIG. 9 is an expanded bottom view of FIG. 1; and,

FIG. 10 is a perspective view of a hair color bottle mixer according to a second embodiment of the present invention, showing the tipper bottle combinable with the lower bottle by a male-female screw thread combination manner. The broken lines shown in drawings depict environment and form no part of the claimed design.
